UNITED STATES PATENT OFFICE.

JOSEPH F. JOY AND JAMES CLARK, OF LOCK NO. 3, PENNSYLVANIA.

HOSE-COUPING.

SPECIFICATION forming part of Letters Patent No. 790,638, dated May 23, 1905.

Application filed November 25, 1904. Serial No. 234,267.

To all whom it may concern:

Be it known that we, JOSEPH F. JOY and JAMES CLARK, citizens of the United States of America, residing at Lock No. 3, in the county 5 of Allegheny and State of Pennsylvania, have invented certain new and useful Improvements in Hose-Couplings, of which the following is a specification, reference being had therein to the accompanying drawings.

10 This invention relates to certain new and useful improvements in hose-couplings, and more particularly to that type of coupling commonly employed upon a train of cars for conveying steam and air from one car to another.

15 The object of this invention is to provide a coupling of the above-described type which may be easily manipulated to form a connection between two cars, and the coupling is constructed whereby the same will be flexible and can adjust itself to the movement of each car.

20 The many other objects and advantages will be apparent from the following description, taken in connection with the drawings, and in 25 describing the invention in detail reference will be had to the drawings accompanying this application, wherein like numerals of reference designate corresponding parts throughout the several views, in which—

30 Figure 1 is a bottom plan view of our improved hose-coupling, showing two sections of hose connected together. Fig. 2 is an enlarged detail view of the flexible joint employed in connection with our improved hose-coupling.

35 Fig. 3 is a transverse sectional view taken on the line $\alpha\alpha$ of Fig. 2. Fig. 4 is a detail sectional view of a sleeve which is used upon the adjoining ends of the hose-sections. Fig. 5 is a detail view of a hanger, and Fig. 6 is a longitudinal sectional view of the flexible joint of our improved hose-coupling.

40 The coupling employed by us is particularly adapted for use upon railway-trains for connecting cars together, whereby steam or air may be conveyed from one end of the train to the other. In connection with our improved hose-coupling we employ two hangers 1, which are adapted to be secured to the bottom face of the sills of railway-cars or secured 45 in any desirable place where it is desired to

5 maintain a coupling between two cars. The hangers are secured to the cars by the screws 2, and each hanger consists of an annular band 3, which is provided with set-screws 4.

Each section of hose is designated by the 55 reference-numeral 5, and as each section is identical in construction we only deem it necessary to describe one of said sections. The hose 5 upon the end of the car is adapted to be retained within the hanger 1 by the set- 60 screws 4. The opposite end of the hose is provided with a metallic collar 6, which is secured thereon by split bands 7, these bands being retained thereon by nuts and bolts 8. In the end of the hose-section 5 which is to 65 be joined to a section of hose carried by another car is placed the joint member 9, this member being retained within the hose by the metallic collar 6. The joint member is provided with an annular flange 10, and the one 70 end of the joint member is formed semispherical, as designated at 11. The joint member is provided with a bore 12, and the end of the bore which passes through the semispherical portion of the joint member is recessed, as indicated at 14, to receive an annular resilient 75 washer 15.

The flange 10 is provided with recesses in its periphery, as designated at 16, and in these recesses are secured the diametrically-opposed 80 spring-arms 17, 17, these arms extending outwardly from said flange and have their outer ends slightly curved, as indicated at 18, 18.

Pivoted to the flange 10 by set-screws 19, 19 is a ring 20. To the opposite 85 sides of the ring are pivoted the bifurcated arms 21, 21 of a sleeve 22, set-screws 23 being employed to pivotally connect said sleeve to the ring 20. The sleeve has a larger diameter than the metallic collar 6, and said sleeve 90 is adapted to surround the collar, as clearly illustrated in Fig. 2 of the drawings. The bore of the sleeve is threaded, as indicated at 23', to receive the end of a spiral spring 24, that is adapted to surround the section of 95 hose 5, the opposite end of the spring being secured adjacent to the hanger 1.

As heretofore stated, the sections of hose 5 are identical in construction, and each is adapted to carry the parts just described, and 100

it will be observed from Figs. 1 and 2 of the drawings that the spring-arms 17 of one joint member are adapted to engage the semispherical end of the opposing joint member. By 5 this means the annular resilient washers 15 will be retained in engagement with one another and the one hose-section placed in communication with the other. It will also be observed that each joint member is pivotally 10 mounted within a ring, which is similarly mounted within a sleeve carried by the end of the hose, and this construction will permit of the adjoining ends of the hose-coupling adjusting themselves to a position common to 15 that of the ends of the cars.

Set-screws 25 may be employed for securing the sleeve 22 in one position in respect to the hose-sections 5 5 and may also be employed for retaining the end of the spiral 20 spring 24 within said sleeve.

The spiral springs 24 are employed for protecting the sections of hose 5 in the different positions which they may assume.

While we have herein shown the preferred 25 manner of constructing our improved hose-coupling, it is obvious that various changes may be made in the details of construction without departing from the general spirit and scope of the invention.

Having fully described our invention, what 30 we claim, and desire to secure by Letters Patent, is—

1. A hose-coupling comprising two sections 35 of hose adapted to be carried by two cars, a joint member carried by each section of hose, means for securing said joint members together, a sleeve pivotally connected to each joint member and a spring attached to each sleeve and surrounding the hose-section.

2. A hose-coupling of the character described; comprising two sections of hose adapt-

ed to be connected together, a joint member carried by each section of hose, means for securing said joint members together, a sleeve pivotally attached to each joint member, said sleeve being formed with an internal thread, a spiral spring surrounding each hose-section and screwing into said sleeve. 45

3. In a device of the character described, the combination of a section of hose, a spring 50 surrounding said section of hose, means for attaching one end of said section of hose and one end of said spring to a car, a coupling member rigidly attached to the opposite end of said section of hose and a sleeve pivotally 55 attached to said coupling member and rigidly attached to the end of said spring.

4. In a hose-coupling for cars, the combination of two sections of hose, means for attaching each section of hose, at one end, to a car, 60 a coupling member carried by each section of hose, a ring pivotally connected to each coupling member, a sleeve pivotally connected to each such ring and a spring connected to each sleeve and surrounding the hose-section. 65

5. In a hose-coupling for cars, the combination of a hose-section, a spring surrounding the hose-section and means for rigidly attaching one end of the hose-section and one end of the spring to a car, with a coupling member carried by the free end of the hose-section, a sleeve attached to the free end of the spring and a universal-joint connection between said coupling member and said sleeve. 70

In testimony whereof we affix our signatures 75 in the presence of two witnesses.

JOSEPH F. JOY.
JAMES CLARK.
